UNITED STATES PATENT OFFICE

2,254,168

PAIL OR CONTAINER

Colin B. Dale, Oak Park, Ill., assignor to Wilson & Bennett Manufacturing Company, Chicago, Ill., a corporation of Illinois

Application December 27, 1938, Serial No. 247,735

5 Claims. (Cl. 221—11)

Certain types of pails or containers are commonly made so that they may be nested for stacking for convenience in storing or shipping. Some of such pails, as for instance those shown in Patent No. 1,974,132, S. A. Bennett, September 18, 1934, have covers provided with central raised portions or embossments which support the superimposed pails. As shown in such patent, a substantial peripheral portion of the embossment is omitted to provide for a pouring spout. When a number of such pails are stacked or nested and such recessed portions come in vertical alignment there is a tendency for the pails in the stack to swing or move towards the sides where the spouts are positioned which occasionally causes the stacks to tip over with consequent loss or damage. It is also the custom in handling such pails, for workmen to tip the stack and roll it along, using the bottom pail as the rolling or supporting element. On account of the depressed spout areas the covers do not provide continuous peripheral support for the superimposed pails and consequently a superimposed pail may tip when the depressed area is on the lower inclined portion of the stack, thus further tending to difficulty in moving the stacks of pails.

The object of the present invention is to provide means applicable to pails of the character set forth, to provide sufficient peripheral support for the superimposed pails to prevent tipping of one pail on another; to provide a spout such as shown in said patent with an attachment for supporting a superimposed pail; to provide a cover having a peripheral upwardly extending bead for engagement with a superimposed pail, said pail also having a peripheral groove in the bottom thereof for engagement with said bead and with said support; and to provide such improvements and advantages as will be described hereinafter.

In the accompanying drawing illustrating this invention,

Figure 1 is a plan view showing a portion of my improved pail;

Figure 2 is a side view of the same;

Figure 3 is a sectional view taken on the line 3—3 of Figure 1; and

Figure 4 is a side view showing one pail resting on another, parts being broken away to show the interengagement of the cover bead with the groove in the bottom of the upper pail.

The pail or container 5 illustrates a steel pail such as commonly made of about five gallons capacity and which is provided with any suitable cover as for instance one of the lug type 6. This cover has a raised or embossed portion 7 forming

the principal portion of the top and a depressed portion 8 in which is positioned the pouring spout 9. As shown in Figure 1 this depressed portion forms a substantial break or recess in the periphery of the raised portion and any superimposed pail resting on the raised portion will ordinarily be unsupported throughout this area. In order that the superimposed or nested pail will be fully supported I provide a support or stacking attachment 10 to provide support for the superimposed pail in this depressed area.

In order to properly support the superimposed pail the support 10 should preferably be located at about the center of the arc defining the outer periphery of the depressed portion 8. However, the pouring spout 9 swings from its retracted position shown in Figure 1 out over the edge and any fixed bracket or support would interfere with the operation of the spout. Accordingly the support 10 is made in the form of a bracket, one end of which is spot-welded or attached at 11 to the side wall of the spout. The bracket then extends up and has a curved or rounded top 12 and continues in a downwardly extending leg having a foot 13 which rests on the top surface of the cover. This construction is such that a relatively small bracket makes a substantially stiff and substantial support and as it moves with the pouring spout, it will not interfere with the operation of the same.

In order to provide an interlocking engagement between the pails each cover has an annular upwardly extending bead 14 around the edge of the raised portion or embossment 7, this bead extending upwardly to the same height or level as the top of the support 10. The bottom 15 of each pail is provided with a peripheral groove 16 which is engaged by the bead and support of the lower pail when they are nested as shown particularly in Figures 3 and 4. It will of course be understood that the pouring spout is in retracted or inoperative position as shown when the pails are thus stacked.

This bead and groove engagement is of particular importance in preventing one pail from slipping or sliding off from another as is apt to occur if the engaging surfaces are merely flat. For instance as shown in Figure 4 the upper pail may be tipped to a considerable angle without disengaging the groove from the bead or projection 14 and these interengaging parts will tend to hold the pails together.

The invention has been illustrated as applied to a particular form of pail but certain features thereof may be adapted to other containers and

therefore I do not wish to be limited to the particular construction herein set forth except as specified in the following claims, in which I claim:

1. The combination with a pail having a cover with a raised portion throughout the main extent thereof adapted to support a superimposed pail and having a depressed portion at one side for receiving a movable spout, a spout rotatably mounted in said depressed portion and adapted to swing out over the edge of the cover, and a support secured to the spout and extending upwardly to the same level as the raised portion of the cover, said support being positioned adjacent to the periphery of the cover when the spout is in retracted position whereby it will coact with the raised portion for supporting a superimposed pail.

2. A pail cover having a raised portion for supporting a similar pail and having a recess in the periphery of the raised portion, a spout movably mounted on the cover in said recess and a support in said recess carried by said spout and adapted to coact with the raised portion for supporting a similar pail.

3. The combination with a can or container having a cover with a raised portion with a recess in the periphery thereof and having a pouring spout movably mounted in said recess, of a brack-

et secured to one side of the pouring spout and extending upwardly to approximately the same height as the raised portion of the cover and adapted to coact with the raised portion in supporting a similar can or container in stacked relation thereto.

4. A pail or the like having a cover, the main portion of which is raised above the top edge or head of the pail and which surrounds an unraised portion adjacent to one side, a pouring spout rotatably mounted in the unraised portion, and a bracket secured to the spout and extending upwardly to the level of the raised portion and then downwardly with its lower end resting on the unraised portion for the purposes described.

5. A container or the like having a cover, the main portion of which is raised above the top edge or head of the pail and which surrounds an unraised portion adjacent to one side, a spout swiveled in the unraised portion, a support secured to the spout and having a bearing on the unraised portion of the cover, said raised portion having a peripheral bead and the support extending upwardly the same distance as the bead, said bead and support being adapted to engage with a groove in the bottom of a similar pail when the pails are in stacked relation.

COLIN B. DALE.
